UNITED STATES PATENT OFFICE

WALTER P. MURPHY, OF CHICAGO, ILLINOIS, ASSIGNOR TO UNION METAL PRODUCTS COMPANY, OF CHICAGO, ILLINOIS, A CORPORATION OF DELAWARE

RAILWAY CAR CONSTRUCTION

Original application filed January 14, 1929, Serial No. 332,326. Divided and this application filed June 22, 1931. Serial No. 545,978.

The device relates to railway freight cars, particularly, to that class of equipment having doors which are opened or "dropped" to discharge part or all of the lading.

5 The object of the invention is to provide a spreader or beam for simultaneous operation of a pair of swingable doors in a railway freight car, which spreader is operated by any of the numerous door raising mechanisms now being marketed. A further object of the invention is to provide such a spreader or beam with spaced apart portions, each of which engages one of the swingable doors so as to permit the door to 10 adjust itself to the frame of the door opening about a substantially vertical axis by a pivotal and/or slidable movement. Any force applied by the operating mechanism adjacent the middle of the spreader is substantially equally distributed to the two doors, and furthermore, the force transmitted to one of the doors by the spreader is substantially equally distributed to the opposite vertical edges or margins of the door. 15

20 In my construction, if the operating mechanism closes one door first, the operating mechanism continues functioning until the other door is closed; furthermore, if one side of one door reaches closed position first, the operating mechanism continues to operate until the other side of such door reaches closed position; in fact, the mechanism operates until all four edges of the two doors 25 reached closed position.

30 A further object of the invention is to reduce the cost and weight of the spreader and car by forming it of a casting so that the metal can be evenly distributed commensurate with the stresses.

35 Another object of the invention is to engage the spreader with the door adjacent a stiffening rib or ribs so that the stresses caused by the lifting of the door will not be taken by the body portion of the door.

In the drawing:

Fig. 1 shows a typical application of my invention to a railway car.

40 Fig. 2 shows a pair of doors with my improved spreader.

Fig. 3 is an enlarged view showing the relation of the spreader and one of the doors.

Fig. 4 shows an end elevation of Fig. 2.

Fig. 5 shows a partial side elevation of a car.

55

Fig. 1 shows a typical application of my invention to a typical so-called "hopper car" wherein the lower portion of the car on each side of the center sills 2 or center ridge is formed into a hopper, each hopper being 60 provided with a swingable door 3. These doors are connected for simultaneous operation by a spreader 8 operated by a mechanism connected to the middle portion thereof and positioned between the center sills 65 and under the ridge for protection from the lading and provided with a shaft extending to opposite sides of the car for operation by a wheel or wrench. There are numerous types of hopper dump cars in service on the 70 railways with the hopper so positioned as to discharge the load between the rails and some designed to discharge the load outside of the rails. There are also dump cars used in the coke service having a floor sloping 75 toward one side of the car with the side wall comprising a plurality of swingable doors to discharge the coke all on one side of the car. My invention is adaptable to any one of the above described cars, or in fact, to any 80 car having two or more doors simultaneously closed by a single operative mechanism.

85 Figs. 2, 3 and 4 show a construction wherein the spreader 55 is loosely connected to each door. The spreader and the doors may be provided with arcuate engaging surfaces 56-57 so that the door is free to slide upon the spreader to accommodate the inequalities of the car. The door is provided with lips 58 which overlie a portion of the spreader so that after the spreader is engaged with the two doors and the two doors are hinged to the car the spreader cannot become disengaged from either of the doors until the 90 hinge pins of one of the doors are removed.

95 In some cars the spreaders are extended to engage locking mechanisms supported by and secured to the side of the car. A common form of locking mechanism comprises a hook 70 which falls into place by gravity 100

and engages the extremities 71 of the spreader, which hook is held in place by a locking cam 72. In some cars these outside locking mechanisms constitute the only means of holding the spreader and the doors in closed position. When it is desired to use such a locking mechanism I extend my spreaders so that their extremities may engage such locking mechanisms.

10 The accompanying drawing illustrates the preferred form of the invention, though it is to be understood that the invention is not limited to the exact details of construction shown and described, as it is obvious that 15 various modifications thereof, within the scope of the claims, will occur to persons skilled in the art.

This is a division of my co-pending application Serial No. 332,326, filed January 14,

20 1929.

I claim:

1. In a railway car, a pair of hinged dumping doors, each provided with a cylindrical bearing, and a spreader having spaced apart 25 cylindrical journals engaging said bearings so as to permit pivotal movement between the door and the spreader about a substantially vertical axis.
2. In a railway car, a pair of hinged dumping doors, each provided with a T shaped 30 groove forming a cylindrical bearing, and a spreader having spaced part portions, each connected to one of said doors so as to permit slidable movement and pivotal movement 35 between the door and the spreader.

WALTER P. MURPHY.
